PISTON

Clyde W. Morrison and James G. Bonine, Toledo,
and Robert E. Marisay, Woodville, Ohio, as-
signors to The Metal Electric Processing Com-
pany, Toledo, Ohio, a corporation of Ohio

Application December 27, 1950, Serial No. 202,858

1 Claim. (Cl. 309—4)

1

This invention relates to pistons such, for example, as are used in compressors for domestic refrigerators, and to the method of making same.

An object is to produce a new and improved piston assembly of the above character, which is made up of two parts, an apertured sheet metal tube to which harmonic motion may be imparted in the usual manner by a revoluble crank pin, and a piston, one end of which has an enlarged surface for contact with the side of the tube to which it is brazed.

Another object is to produce a method of forming a piston and tube assembly by which the two parts can be readily and conveniently formed individually, and efficiently and economically assembled, so that in effect a unitary structure is produced which is light in weight, sturdy and rigid in construction, requires a minimum of machining, enables the use of flat sheet metal for one part, and effects a liquid-tight seal between the parts.

A further object is to produce a piston and tube assembly of the above character which has enlarged contact area between the parts to insure a rigid joint liquid-tight in its nature, the same being light in weight, and inexpensive to manufacture on a quantity basis.

Other objects and advantages will hereinafter appear, and for purposes of illustration but not of limitation, embodiments of the invention are shown on the accompanying drawings, in which

Figure 1 is a perspective view of the tube and piston assembly;

Figure 2 is an elevational view partly in section of the assembly shown in Figure 1;

Figure 3 is a side elevation of the assembly shown in Figure 1;

Figure 4 is a perspective view of the apertured sheet metal strip before it is rolled to form the tube;

Figure 5 is a top perspective view of the piston with its end formed to conform to and fit the tube;

Figure 6 is a side elevation of an alternate form of a drawn shell; and

Figure 7 is an enlarged fragmentary sectional view showing a means for holding the parts in assembled relation preliminary to the controlled atmosphere brazing.

The illustrated embodiment of the invention comprises a tube and piston assembly, the parts of which consist of a piston 10 and a tube 11 rigidly joined to the piston. By way of example, this assembly is adapted for use in a refrigerator compressor, the piston reciprocating in the usual

2

manner within a cylinder and the tube 11 having aligned lateral openings 12 of longitudinally elongate form to receive a slide on the end of a revoluble crank pin thus producing the well-known harmonic or Scotch motion. The piston 10 is cylindrical and in one form, the outer end is closed by a disc 13 which fits snugly inside the piston and is brazed in a controlled atmosphere to effect a rigid fluid-tight seal.

10 An alternate form of the piston is shown in Figure 6 which instead of being formed from a tube, is in the form of a drawn shell having an integral end wall 13a.

The inner end of the piston is formed in a suitable manner to provide laterally extending end flanges 14 and upstanding side flanges 15 which conform to and fit the outer contour of the tube 11 in the region between the aligned apertures 12. By forming the inner end of the piston in this manner, an enlarged surface contact between the end of the piston and the tube can be achieved so that when the parts are brazed together, this increased surface affords the opportunity of effecting a very secure, rigid and leakproof joint between these parts so that for all practical purposes, a one-piece unitary assembly is produced.

The tube 11 is formed from a strip A of sheet metal in which the holes 12 are first blanked 30 whereupon the strip is rolled to form a tube with the free edges in abutting relation as indicated at B on Figure 2. The tube and piston are assembled with these abutting edges disposed within the formed end of the piston so that in the 35 subsequent brazing operation, not only is the piston rigidly secured to the tube, but also the abutting edge portions of the tube are secured together to provide in effect a continuous walled tube.

40 It will be understood that after the parts are formed as above explained, they are introduced in a brazing furnace and it is therefore necessary temporarily to attach these parts together so that they will be properly retained in position during

45 the brazing operation. For this purpose, the parts may be connected together by projection welding in a resistance welder, or tack welded, this being indicated on Figure 2 at C. Alternatively, the upstanding flanges 15 which preferably reach close to the edges of the openings 12, may be crimped over as indicated at 16, to provide the temporary connecting means. Thereafter, the assembly is introduced into the furnace 50 and the formed end of the piston as well as the

abutting edges **B** of the tube **11**, and where a separate disc **13** is used, are all brazed in a controlled atmosphere to effect the desired rigid leak-proof joint.

The advantages of the above described assembly are numerous. In the first place, the assembly is very light in weight and this is important not only from the standpoint of performance but also from the standpoint of material cost saving. This structure can be completed readily for use with a minimum of machining, a small amount of finish machining being required. The rigid joint between the parts not only provides the equivalent of a one-piece structure, but also seals the inside of the piston against the entrance of oil or the like which would not only be deleterious but would also interfere with the proper operation of the piston. By making the piston of tubing or drawn shell, the proper outside diameter can be secured with but little finish machining. Also by employing a rolled blank to produce the tube, machining costs on all surfaces are saved.

It is to be understood that numerous changes in details of construction, arrangement and choice of materials may be effected without departing from the spirit of the invention especially as defined in the appended claim.

What we claim is:

A piston and tube assembly comprising a cylindrical tube having abutting longitudinal edges and a pair of aligned transverse slots, a cylindrical piston, means closing the outer end of the piston, a continuous and curvilinear flanged cradle-like portion integral with the inner end of said piston and contoured to fit snugly the adjacent cylindrical surface of the tube on opposite sides of the abutting edges, and a brazed joint between the flanged piston end portion and the tube and between the abutting tube edges thereby rigidly connecting the parts and sealing the interior of the piston.
